UNITED STATES PATENT OFFICE

154,600

DESIGN FOR A TEXTILE FABRIC OR SIMILAR ARTICLE

Jean Godart, Manhasset, N. Y., assignor to Robertson Fabrics, Inc., New York, N. Y., a corporation of New York

Application August 10, 1948, Serial No. 148,033

Term of patent 3½ years

(Cl. D92—1)

To all whom it may concern:

Be it known that I, Jean Godart, a citizen of the Republic of France, residing in Manhasset, county of Nassau, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric showing my new design.

The dotted lines outline a design unit which unit is repeated over the fabric in regular succession as indicated by the extensions beyond the unit boundaries.

I claim:

The ornamental design for a textile fabric or similar article, as shown and described.

JEAN GODART.
